UNITED STATES PATENT OFFICE.

ROBERT E. YOST, OF YORK, PENNSYLVANIA.

PAPER-REGISTERING DEVICE.

Application filed October 28, 1921. Serial No. 510,573.

To all whom it may concern:

Be it known that I, ROBERT E. YOST, a citizen of the United States, and a resident of York, county of York, State of Pennsylvania, have invented certain new and useful Improvements in Paper-Registering Devices, of which the following is a specification.

This invention relates to a paper register-10 ing device for properly positioning sheets of paper on the platen of printing presses.

The object of this invention is to provide a paper registering device of a character which can be attached at any location to the 15 face of a printing press platen and thereby rendering the same adaptable for use on very small as well as large sheets of paper.

A further object is to construct a device of this kind of the smallest possible size; 20 this is a very important feature for the reason that there is seldom if ever much space available at the point where it is necessary for this device to be placed for performing its functions. The printing press 25 constructions of the present day does not afford much room for a device of this kind.

Another object of this invention is to construct a practical operative device, of the character herein shown and described, which 30 has practically all its working parts enclosed in substantially a dust proof casing, so that the same is durable and otherwise fool proof.

Other objects will be apparent, and the 35 nature and scope of this invention will be more fully understood, from the following description, taken in connection with the accompanying drawings, forming a part hereof and, in which similar numerals refer 40 to similar parts throughout the several views.

Fig. 1, is an enlarged view of a paper register-45 ing device attached to the platen of a printing press, and is shown in operating condition.

Fig. 2, is a sectional view of Fig. 1, taken on line 2—2.

Fig. 3, is a view of the paper registering device with the top plate removed, showing the internal mechanism.

Fig. 4, represents certain essential parts 50 of a printing press with which this paper registering device co-operates.

Referring to the drawings, 1 is a base section 55 of the paper registering device and carries a boss 3 upon which is journaled the disk 4. The top plate 5 is provided with a

counter bore 6 which fits neatly on the boss 3 and is held firmly thereto by the screw 7.

In addition to being bored to fit the boss 3, the disk 4 is provided with an opening 8 60 to provide space for the spring 9 and the stop-pin 10. Forming a part of the base section 1 is a projection or pin 11, around which is wound the spring 9 as shown. The spring 9 normally turns the disk 4 in the di- 65 rection indicated by the arrow 12, relative to the base section, until it is prevented from turning by coming in contact with the pin 10 at the point 13.

Forming part of the disk 4 is a lug 14, 70 a cord 15 being attached to the same through the link 16 which fits into the hole 17 as shown. When tension is applied to the cord 15, the disk 4 turns on the boss 3 against the action of the spring 9, and carries with it 75 the paper gripping clips 18 and 19, the same being firmly fixed thereto by solder or other means.

The printing press platen 20 is covered with padding 21 in the usual manner. Soldered to the rear side of the base section 1 are needles 22 which are inserted into the padding 21 to hold the paper registering device to the printing press platen.

The operation of this device is as follows: 85

The paper registering device is fixed to the printing press platen at the location indicated at A, Fig. 4. The cord 15 is led downward and firmly tied to the eye pin 23. It is very apparent to those skilled in the 90 art, how tension will be applied to the cord 15 during the operation of the printing press when connected as above described; in that, during the forward movement of the platen 20 the paper holder 31 moves in the direction 95 indicated by the arrow 24 relative to the platen, the same turning on the pivot 25. As this occurs the end of the eye pin 23 moves in the direction indicated by the arrow 26 relative to the platen, thereby applying tension to the cord 15 and turns the disk 4 on the boss 3. The paper gripping clips 18 and 19 are thereby moved in the direction indicated by the arrow 27, Fig. 1. The length of the eye pin 23 and the cord 15 100 must be such whereby the paper gripping clips will be carried from the position shown in full lines in Fig. 1, to the position shown in light broken lines. As soon as tension is released on the cord 15 the spring 9 carries 105 the disk 4 and the paper gripping clips 18 and 19 back to normal position.

The action this registering device has upon the paper is as follows: The paper 29 is layed upon the platen at approximately the correct location for perfect registration; 5 during this operation the paper will naturally find its way between the paper gripping clips 18 and 19; the tension of these paper gripping clips being just sufficient to give enough gripping action on the paper 10 so that during the movement of the paper gripping clips from the position shown in full lines Fig. 1, to the position shown in light broken lines, they will carry the paper in substantially the direction indicated by 15 the arrow 30, until the edge of the paper comes in contact with the stops 28 at which time the paper is in perfect registration; the paper gripping clips continue to move forward, sliding on the paper, and finally release 20 their gripping action upon the same entirely; this must occur before the platen presses the paper against the type so that it does not interfere with printing on the entire surface of the paper.

25 It is obvious that all the adjustments must be such whereby the paper 29 is perfectly registered by this device before the paper holder 31 arrives at the position indicated by 31', for the paper holder is then holding the 30 paper firmly against the platen to prevent the same from shifting, and under this condition the registering device cannot move the paper to bring it to perfect registration.

In constructing a device of this character 35 I prefer to have the paper gripping clips inclined slightly from vertical position in the direction toward its forward movement as shown in Figs. 1 and 3; because I have found that if they are vertical, there is too 40 much effort applied to move the paper against the side paper stops, relative to that applied for pulling it down against the lower stop.

Having thus described my invention what 45 I claim and desire to secure by United States Letters Patent is as follows:

1. In combination with a printing press having a platen and a moving crank element, of a base element, means for attaching 50 said base element at any point on the face of the platen, a lever pivoted to said base element, paper gripping means carried by said lever, a flexible cord connecting said lever with said crank element and adapted 55 to move said lever through the action of said moving crank element, and means for returning said lever to normal position.

2. A paper registering device comprising a base element, needles fixed to a said base 60 element, a lever pivoted to said base element, a flexible cord attached to said lever, a stop for limiting the movement of said lever, a spring for normally holding said lever against said stop, and paper gripping means 65 carried by said lever.

3. A paper registering device comprising a circular base element, a circular disk journaled thereon, a stop for limiting the movement of said circular disk, a spring for normally holding said disk against said stop, 70 a lug carried by said circular disk and projecting beyond said circular base element, paper gripping means carried by said circular disk, and a plate fixed to said circular base element and substantially enclosing said 75 circular disk, said spring and said stop in a dust proof case.

4. A paper registering device comprising a base element, means for attaching said base element to a printing press platen, a lever pivoted on said base element, a stop for limiting the movement of said lever, a spring for normally holding said lever against said stop, paper gripping means carried by said lever, and means for moving 80 said lever against the action of said spring in unison with the movement of the said printing press platen.

5. A paper registering device comprising a circular base element, a circular disk journaled thereon, means for attaching said base element to a printing press platen, a stop for limiting the movement of said circular disk, a spring for normally holding said circular disk against said stop, a lug carried by 90 said circular disk and projecting beyond said circular base element, paper gripping means carried by said circular disk, a plate fixed to said circular base element and substantially closing said circular disk, said 95 spring and said stop in a dust proof case, and means for moving said disk through said lug against the action of said spring in unison with the movement of the said printing press platen.

6. A paper registering device comprising a base element, needles for attaching said base element to any point on the face of a printing press platen, a lever pivoted to said base element, a stop for limiting the 100 movement of said lever, a spring for normally holding said lever against said stop, paper gripping means carried by said lever, and means adapted to move said lever against the action of said spring in unison 105 with the movement of the said printing press platen.

7. A paper registering device comprising a base element, a lever pivoted thereto, a stop for limiting the rearward movement of 110 said lever, a spring for normally holding said lever against said stop, and paper gripping means fixed to the hub of said lever, the same being slightly inclined from vertical position in the direction toward its forward movement when said lever is against 115 said stop.

In testimony whereof I affix my signature.

ROBERT E. YOST.
